WASHING MACHINE WRINGER

Frank Breckenridge, Mansfield, Ohio, assignor to
 Westinghouse Electric & Manufacturing Company,
 East Pittsburgh, Pa., a corporation of
 Pennsylvania

Application May 23, 1939, Serial No. 275,164

3 Claims.

(Cl. 240—2)

My invention relates to washing machine wringers and more particularly to the design and construction of internally mounted illuminating structures therefor.

With those wringers known to the art which have had a light incorporated therewith, it has been necessary to clamp a removable lamp to the outside of such wringer frame. These lamps have usually been in the form of the well known goose-neck construction which required the operator to bend the light from side to side depending upon the exact position it is desired to have the light. This particular arrangement of a lamp structure is not only unsightly but is in an operator's way.

It is, therefore, an object of my invention to provide and locate a light or lights within a wringer frame in such a manner that the light therefrom may be thrown on the wringer rolls as well as into the wash tub and the receptacle into which the wrung clothes are discharged. When electric power wires are associated with a wringer frame or structure, it has been necessary to bring the wire or wires from the washing machine structure proper to the wringer frame on the outside of the housing. By having the electric wires located outside a suitable mechanical sheath, such wires are subjected to the sloppage from the washing tub as well as the additional danger of the operator coming in contact with them. A further disadvantage of having the wires located on the outside of the housing or wringer head is that the wires may eventually become twisted as the wringer is rotated about the drive shaft as an axis causing such wires to become broken and crossed resulting in the possibility of grounds to the frame or a serious shock to an operator.

It is, therefore, a further object of my invention to provide means located within the wringer housing or frame for conducting power wires into such wringer frame without causing them to become twisted or crossed as the wringer head is swung about a vertical drive shaft as an axis, for preventing sloppage from the washing machine tub from contacting the conducting means in any manner whatsoever, and for preventing an operator from coming into contact with such conducting means.

A still further object of my invention is to provide a rugged, inexpensive, fool-proof structure for conducting power into a wringer for use with lights or power switches, or the like.

Other objects of my invention will either be pointed out specifically in the course of the fol-

lowing description of a device embodying my invention, or will be apparent from such description:

Referring to the accompanying sheets of drawings:

Figure 1 is a side elevational view, partly in section, of a wringer embodying my invention;

Fig. 2 is a top plan view of the device shown in Fig. 1;

Fig. 3 is a top plan view of the device shown in Fig. 4;

Fig. 4 is a side elevational view of a modified form of the device embodying my invention;

Fig. 5 is an enlarged sectional view taken along the line V—V of Fig. 2;

Fig. 6 is an enlarged sectional view taken along the line VI—VI of Fig. 3;

Fig. 7 is a sectional view taken along the line VII—VII of Fig. 6;

Fig. 8 is a sectional view taken along the line VIII—VIII of Fig. 6; and

Fig. 9 is a sectional view taken along the line IX—IX of Fig. 8.

Referring to Figs. 1, 2 and 5 of the accompanying drawings, I show a wringer 12 having a frame 16, transmission housings 20, transmission mechanism 24, an interlocking device 26, an auxiliary clutch 28, illuminating device 38 and electrical energy-translating device 41, therefor.

The wringer 12, including frame 16, transmission housing 20 having located therein the transmission mechanism 24 and the auxiliary clutch 28 operatively associated therewith is fully described in my copending application Serial No. 288,311, filed August 4, 1939. The interlocking device 26 is fully described in my copending application Serial No. 275,165, filed May 23, 1939.

The illuminating device 38 operatively associated with wringer 12 above the transmission mechanism 24 and housing 20, comprises a lamp 462, a receptacle 464, and a reflector shield member 466 having open-mouthed louvres 468 located on each side thereof. The lamp 462 and the receptacle 464 are located within the reflector shield 466, which is, in this instance, located upon and removably attached to the wringer 12 above the transmission housing 20 and at the side of a removable longitudinally extending wringer top cover 112.

The reflector shield 466 is, in this instance, a light weight metallic cover plate which may have a light-reflecting interior surface to increase the operating efficiency thereof. The reflector shield 466 may be attached to the wringer by means of

a resilient latching member 470 attached to the inner surface of the reflector and cooperating with a notched latch 472 attached to the transmission housing 20. The resilient member 470 by cooperating with the latch 472 permits the shield 466 to have a "snap-on" connection with the housing 20. However, it is to be understood that such snap-on reflector shield may be located in any desired position on the wringer and that such reflector shield is to be considered part of the wringer housing. In other words, the lamp 462 located within the reflector shield will then be located within the wringer housing regardless of the position and location of the reflector on the wringer.

The lamp receptacle 464 may be rigidly attached to the wringer frame 16 by means of a lock nut 474 cooperating with a threaded nipple 476 associated with the receptacle. The nipple 476 is inserted through an aperture 478 in the side walls of the wringer frame 16. Electric wires 480 connecting the lamp to a source of power (not shown), are brought out through the nipple 476 and down through the wringer housing 16 to the electrical energy-translating device 41 which conducts electric energy into the wringer in a manner hereinafter described. The lamp 462 is inserted within the receptacle 464 and, is, therefore, operatively associated with a power supply (not shown) through the cooperation of the translating device 41.

With the lamp located within the receptacle 464 and reflector shield 466, and operatively associated with a power supply, light may be emitted therefrom and will be reflected by the inner surface of the reflector out through the open louvres 468. A pre-focused lens 482 may be located in the outer open portion of the louvres 468 so as to focus a portion of this light over the end portion 422 of the drain shield 88 along the wringer rolls, a portion down in the wash tub 484, and a portion into a receiving receptacle such as a basket located on the delivery or exhaust side of the wringer.

It is, therefore, obvious that the lamp 462 located within the housing of the wringer 12 will, by means of the illustrated suitable louvres and lens, illuminate both sides of the wringer rolls and drain shield or clothes chute, the wash tub, and the receiving basket located on the other side of the wringer. With such an illumination of a wringer, it would be possible to use such wringer in a position having poor or no other illumination without an operator being endangered, such as, by sticking her hands into the wringer rolls. In other words, a washer equipped with a wringer having a light within the wringer housing which will illuminate the ringer rolls, the wash tub and receiving receptacle may be used with the utmost safety and convenience in any desired location, even where there is no other light source.

When incorporating a light source with wringers having a curved or rounded top surface it is advisable if not absolutely necessary to have the lights mounted directly upon and close to the operating mechanisms thereof. Accordingly, referring to Figs. 3, 4, 6 and 7, I show a modified and preferred form of wringer illumination. I show a wringer 10 having a frame 14, transmission housing 18, transmission mechanism 22, an illuminating device 40 and an electrical energy-translating device 43 therefor.

The modified illuminating device 40, for illuminating the wringer, wash tub and receptacle, 75

comprises a plurality of lamps 490, (see Fig. 7) located within the shoulders 52 of the clothes chute or drain shield 50, a plurality of receptacles 492 and suitable supporting brackets 494 therefor.

5 The brackets 494 are, in this instance, rigidly attached to an inwardly extending protrusion 178 by means of suitable screws 496 (see Figs. 6 and 7). The brackets 494 are bent inwardly and downwardly so that the lamps 490 operatively 10 associated therewith extend up within the shoulders located at the end of the clothes chute or drain shield.

Apertures 498 are located on the top portion 15 at the inside of the shoulders 52 of the drain shields (as shown by dotted lines in Fig. 7). The apertures 498 are located in such a position, relative to the lamps 490 and the wringer rolls 66 and 68 that the light emitted by such lamps will be directly transmitted from the inside of the shoulders through the apertures onto the wringer roll. 20 By having the bottoms of the shoulders 52 open, which is a common practice, a portion of the light emitted from the lamps 490 will be directed downwardly through the shoulders and accordingly 25 illuminate the wash tub 484 and a receiving receptacle on the other side of the wringer. This light will be directed toward the center of the wash tub because of the particular shape of the shoulders 52, see dotted lines on Fig. 4 which illustrate the path of the light rays. In other words, 30 one of the lamps 490 will illuminate one side of the wringer rolls, clothes chute or drain shield by the light transmitted through the aperture 498, and will illuminate either the wash tub or 35 receptacle by the light which is directed downwardly through the shoulders 52, whereas the lamp located on the transversely opposite side of the wringer will illuminate the opposite side of the wringer rolls, clothes chute or drain shield 40 and either the receptacle or the wash tub.

It is to be understood that the brackets 494 and lamps 490 may be located in either end, or in both ends of the wringer, if desired, in which case said brackets and lamps are substantially 45 duplicated. It is, therefore, obvious that by utilizing this device embodying my invention, it is possible to illuminate the wringer rolls, the wash tub and clothes receptacle by means of lamps located entirely within the wringer housing.

50 It is preferred that a sheet of translucent or transparent material such as glass 500 be located within the apertures 498 substantially as shown in Figs. 8 and 9 to prevent moisture from being 55 splashed upon the lamps. The glass 500 may be inserted within a notched groove 502 (see Fig. 9) located within the shoulder 52 or in any other desirable manner. The glass is then retained 60 within the groove 502 by means of a resilient member 504 (see Fig. 8) which may be swingably mounted upon the frame 14. The swingably 65 mounted resilient member 504 may be positioned under the glass 500 in such a manner that, as the glass is slid or positioned within the groove 502, such resilient member will move under the glass and retain it within the groove 502. By having a translucent or transparent member, such as glass, located within the aperture 498, the moisture contained within the clothing run through the wringer cannot splash or get into the wringer frame in any manner whatsoever, so as to injure the electrical connections associated with the lamps or electrical translating device 43.

70 It is, therefore, obvious that the illuminating devices 462, 490, or the like, may be located within

the wringer frame itself or within a portion of the wringer housing, and that the wringer frame may be utilized as a reflector for directing light, or that a portion of the housing may be removably attached to the frame to direct such light in the manner hereinabove described.

Electric power is transmitted into the wringer housings by means of the electrical translating devices 41 or 43, shown with wringers 12 and 10 in Figs. 5 and 6, respectively. However, it is to be understood that the translating devices may be interchanged or used with any desired swing-
ing wringer.

The translating device 41 shown in Fig. 5 comprises a substantially flat insulating annulus 501 having a plurality of annular grooves 503 cut or positioned therein. The insulating annulus 501 is preferably formed of a phenolic resin. Metallic electric conducting rings 505 are placed within the grooves 503 and are operatively associated with a suitable electric supply cable 507 which is adapted to connect to a power supply, (not shown).

The insulating annulus 501 is positioned within an annular slot located in the upper surface of the wringer support bracket 326 of wringer structure 12 which is rigidly attached to the washing machine tub 484.

Suitable electrical pick-up fingers 509 are insulatedly attached to the inner surface of the wringer transmission housing 20 by means of an insulating block 511. The fingers 509 are shaped so as to be located within the grooves 503 and to contact the metallic conductor rings 505.

The electric cable 480, operatively associated with the lamp 462, as hereinabove described, is directly connected to the fingers 509. It is, therefore, obvious that, through the cooperation of the electrical translating device 41, power will always be available for the lamp 462, or any other electrical device placed within the wringer housing.

The electrical translating device 43, shown in Fig. 6, as being operatively associated with wringer 10, comprises a plurality of conducting sleeves 513 insulated from each other and the transmission housing 18 by suitable insulating sleeves 515. This composite structure of conducting and insulating sleeves 513 and 515 is positioned within an annular groove 517 in the bearing plate 46 upon which the wringer 10 rotates. An insulating ring 519 is positioned in the bottom of the groove 517 to insulate the bottom edges of the conducting sleeves 513 from the plate 46. The power cable 507 is operatively associated with the conductor sleeves 513 to connect them to any suitable power supply (not shown).

The conductor and insulating sleeves 513 and 515 are progressively shorter from the inner to the outer insulating sleeve. This arrangement results in each of the conductor sleeves 513 being exposed at their upper ends. Flexible electrical pick-up fingers 521, accordingly, may then cooperate with the upper or exposed portions of the conductor sleeves 513. These fingers 521 are insulatedly attached to the transmission housing by means of an insulating block 523, and are associated with the electric conductor 481 leading to lights 480. The fingers 521 are positioned, in this instance, substantially in line with the conductor sleeves 513 rather than being normal thereto.

This arrangement permits the wringer structure to be freely and readily removed from the washer without causing any injury to the fingers or such structure.

It is obvious that with the electrical translating devices positioned within the wringer housing that the sloppage from the washer cannot in any way contact the devices so as to injure them or cause the cooperating parts thereof to corrode.

It is, therefore, apparent that with a light source mounted within and attached to a wringer so as to be free from sloppage, and with an electrical translating device operatively associated therewith, which is also free from any moisture or sloppage, for readily conducting electrical energy to the lamps, as hereinabove described, such wringer may be safely operated in any position, even where there is little or no other light source.

Various modifications may be made in the device embodying my invention without departing from the spirit and scope thereof, and I desire, therefore, that only such limitations shall be placed thereon as are imposed by the prior art and the appended claims.

I claim as my invention:

1. In combination, a wringer including a frame, a set of rolls and a clothes chute located on each side of the rolls, said clothes chutes having upstanding shoulders at each end thereof, a plurality of lamp-sockets, a plurality of light sources comprising lamps operatively associated with said sockets, means comprising irregularly-shaped brackets for rigidly attaching the lamp sockets to said frame and for supporting the lamps within said upstanding shoulders, and means comprising apertures located within said shoulders for directing the light from said light sources to illuminate both sides of said rolls and both clothes chutes.

2. In a wringer construction, the combination of a frame having clothes chutes disposed on opposite sides thereof and hollow shoulders extending transversely of the frame at adjacent ends of the clothes chutes, a pair of rolls journaled in the frame and disposed intermediate the clothes chutes, said shoulders having respective apertures therein on opposite sides of the rolls and lighting means arranged within the respective hollow shoulders, the construction and arrangement being such that light is projected through said apertures upon both sides of the rolls and upon both of said clothes chutes.

3. In a wringer construction, the combination of a frame, a pair of rolls journaled in the frame, a pair of clothes chutes carried by the frame on opposite sides of the rolls, said frame including a pair of hollow shoulders extending transversely of the frame at adjacent ends of the clothes chutes, said shoulders having respective windows therein above the ends of the clothes chutes and said shoulders having openings in the bottoms thereof, and lighting means arranged within the respective shoulders for projecting light through said windows upon both sides of the rolls and upon both clothes chutes and downwardly through the openings in the bottoms of the shoulders to a region disposed below the shoulders and the clothes chutes.
